UNITED STATES PATENT OFFICE.

JOSEPH DICK, OF CANTON, OHIO.

DESIGN FOR A FAN-CASING AND FRAME FOR FODDER-CUTTERS.

SPECIFICATION forming part of Design No. 31,489, dated September 5, 1899.

Application filed July 10, 1899. Serial No. 723,428. Term of patent 14 years.

To all whom it may concern:

Be it known that I, JOSEPH DICK, a citizen of the United States, residing at Canton, in the county of Stark and State of Ohio, have 5 invented new and useful Improvements in a Design for a Supporting - Frame and Fan-Casing for Fodder-Cutters, of which the following is a specification.

My invention relates to a new and original 10 design for a supporting-frame and fan-casing for fodder-cutters.

The design consists of a substantially cylindrical casting of the configuration shown 15 in the accompanying drawings, in which— Figure 1 is a perspective view from the front. Fig. 2 is a perspective view from the rear. Fig. 3 is a vertical sectional view through the center of the fan-casing.

In the drawings, A represents a substantially cylindrical casting having upon its forward end an opening a, substantially heart shape in form and having around its edge a projecting flange b and radial ribs c, d, e, and f, diverging therefrom and terminating in the 25 circumference of the fan-casing. Said radial ribs d and e connect with projecting lugs g and h, which form the base or support of the fan-casing. At the base of the opening a and upon both sides of the fan-casing there is 30 formed a journal-bracket i. Upon the face of the forward end of the fan-casing there is provided an opening i', having the project-

ing oppositely-disposed lugs k and l. Upon the circumference or rim of the fan-casing A there is formed a discharge-pipe B, substantially tubular in form, having formed thereon a circumferential rim m. On the reverse side or rear of the fan-casing the heart-shaped opening is broken by the curved aperture n on the top thereof and having oppositely-disposed projecting lugs j and l' and the oblong opening o on the side thereof, provided with a projecting flange p, terminating at its lower end in a plate q, connected with a corresponding plate r on the opposite side 45 thereof by the rib s. In the circumference or rim of the fan-casing and at one side thereof there is provided the opening t, having a ribbed edge u and projecting lugs j' and l'.

The essential features of the design consist of the substantially cylindrical fan-casing A, provided with central openings and the projecting radial ribs.

What I claim is—

The design for a fan-casing and frame for 55 fodder-cutters herein shown and described.

In testimony whereof I have hereunto set my hand in the presence of two subscribing witnesses.

JOSEPH DICK.
